APPARATUS FOR DYEING, BLEACHING AND OTHER LIQUID TREATMENT OF A MATERIAL IN GRANULAR, THREADED OR FIBROUS FORM

Per-Gustaf Mellgren, Avesta, Sweden, assignor to Aktiebolaget Pluria, Stockholm, Sweden, a corporation of Sweden

Application April 19, 1955, Serial No. 502,297

Claims priority, application Sweden April 22, 1954

6 Claims. (Cl. 68—190)

To carry through a dyeing process, it is of the utmost importance that it is possible, starting from a labile initial state with a maximum concentration of dye in the dyeing bath and with no dye on or in the material to be dyed, to reach in the shortest possible time a final state, in which there is a minimum concentration of dye in the dyeing bath, and the distribution of dye on or in the material is completely uniform.

This object can be achieved by means of certain known methods which are useful in bleaching or other liquid treatment and involve a particular manner of utilizing impregnation in vacuum, by means of which a more even and rapid start of the dye fixing process is achieved and a liquid movement which conforms as closely as possible to the theory and practice resulting in a more rapid fixation and equalization of the colour and which comprises frequent reversals of the direction of flow of the dyeing bath (pulsation).

The present invention relates to an apparatus which is particularly well suited for the performance of said process in dyeing, bleaching or other liquid treatment of material in granular, threaded or fibrous form. In accordance with the present invention, the apparatus comprises a container adapted to confine the material to be treated, a vessel in which the treatment liquid is prepared and stored, a pump adapted to operate either as a vacuum pump or as a compressor, and conduit means interconnecting said container, said vessel and said pump so that the container may be evacuated, the treatment liquid may be caused to perform a pulsating movement through the material and air may be blown through said container.

The conduit means may be connected to a source of compressed air by means of which the treatment liquid may, during the pulsation, be subjected to a constant superatmospheric pressure.

In accordance with this invention it is possible to replace the pulsating movement of the treatment liquid by a heating of the material to be treated without drying it. For this purpose, the conduit means may be connected to a steam supply, from which steam admixed with air is supplied to the material impregnated with the treatment liquid.

The invention will be explained in detail below, reference being had to the accompanying drawing, which shows diagrammatically an embodiment of the apparatus.

As shown on the drawing, the apparatus comprises a container 1 in which material supports 2 for, e. g., crossed coils of yarn (yarn wound on perforate sleeves) may be placed, e. g. for dyeing, and a closed expansion vessel 3, in which the treatment liquid (the dyeing bath) is prepared and is heated by means of steam coils 4, e. g. to 110° C. With the aid of a pump 5 which is adapted to be used either as a vacuum pump or as a compressor, the container 1 is evacuated for which purpose a valve 7 in a conduit 6 communicating with the container 1 is opened, a four-way valve 8 is positioned so that com-

2

munication is set up between the conduit 6 and the conduit 9 wherein the pump 5 is disposed and finally a valve 10 is opened. When the maximum degree of vacuum (e. g. about 85—95%) is reached in the container 1, the valves 7 and 10 are closed.

To be able thereupon to subject the entire system to a certain constant superatmospheric pressure, e. g. 0.7 kilogram per square cm. above atmospheric, a reducing valve 12 in a pressure conduit 11 is opened and adjusted to the desired superatmospheric pressure. To prevent overloading of the pump 5 when this operates as a compressor, an automatically operating unloading valve 13 is arranged between the high-pressure and low-pressure sides of the compressor, so that a suitable pressure difference may be maintained between the two sides of the compressor. At the same time a valve 15 arranged in a conduit 14 between the four-way valve 8 and the vessel 3, is opened. From this moment, the pump 5 operates as a compressor. Thereupon, a valve 16 is opened, which is disposed in a conduit 17 branched out from a conduit 18 connecting the container 1 and vessel 3. Thereby the dyeing liquid will flow from the vessel 3 to the container 1. Since the material to be dyed is usually dry and, due to the evacuation of the container 1, the air is removed from all fibres and interstices, a very rapid impregnation of all pores of the material with dyeing liquid will be obtained. This results in the best possible initial state for the subsequent dyeing process.

When the dyeing liquid in the container 1 covers the material, a valve 19 in the conduit 18 is opened and simultaneously the valve 16 is closed, so that more dyeing liquid from the vessel 3 flows into the container 1 through the conduit 18, until a limit level 20 is reached in the container 1. At this moment a float-operated non-return valve 21 is automatically closed, whereby the dyeing liquid in the container 1 is prevented from entering the conduit 6. The valve 7 is now closed and the four-way valve 8 is operated by means of an impulse transmitting device (not shown) in a manner such that the high-pressure side of the compressor 5 communicates alternately with the container 1 over the valve 7 and the conduit 6 and with the vessel 3 over the valve 15 and the conduit 14. Thereby, the dyeing liquid will be caused to pulsate between the container 1 and the vessel 3 through the material to be dyed; suitably, this pulsation is carried out so that the dyeing liquid will always cover the material.

If desired, a certain amount of dyeing liquid may be caused to enter the container 1 without being forced through the material to be dyed. For this purpose a valve 22 in a branch conduit 23 may be used. This valve 22 suitably consists of a non-return valve so that the dyeing liquid can flow through the valve 22 only in the direction from the vessel 3 towards the container 1. Thereby the advantages are obtained that a uniform concentration of dye is obtained throughout the dyeing bath, that a greater amount of liquid is circulated through the material in a direction from outside and inwards into the material, whereby the equalization is augmented and further that the liquid level in the container 1 is prevented from being lowered, since the liquid will always flow more easily from the vessel 3 to the container 1 than in the opposite direction.

After e. g. 10 to 15 minutes of pulsation the dye is completely affixed to the fibre and uniformly distributed through the material, whereby the dyeing process is finished.

In order to rinse the material, the dyeing liquid is removed from the container 1. This may be achieved e. g. by opening a valve 24 communicating with the conduit 18 and the valve 16, whereby the spent dyeing liquid is drained from the container 1 and the vessel 3. There-

upon, the major portion of the remaining dyeing liquid in the material is removed by blowing air therethrough. For this purpose, the pump 5 will be made use of, in that after opening the valve 24, air is supplied to the pump 5 through a valve 25 and is forced into the container 1 through the four-way valve 8, which has been adjusted to the requisite position, and through the conduit 6. Thereafter, the container 1 is evacuated in the manner described above, whereupon rinsing water is introduced via a valve 26.

The rinsing operation may be effected by evacuating the container 1, filling it with rinsing liquid and draining the material in a repetitive sequence or by allowing the rinsing liquid to flow continuously through the material.

If it is desired, during a dyeing process performed at a temperature above 100° C., to check the result by opening the container 1, this may be achieved by forcing the entire dyeing liquid out of the container 1 and back to the vessel 3, whereupon the valves 16 and 19 are closed and the valve 24 opened. Thereby, the pressure and temperature of the liquid remaining in the material are quickly and in a simple manner reduced to atmospheric pressure and 100° C. by vaporization, whereupon the cover of the container 1 can be raised.

In certain cases, it may be desirable to cool the dyeing bath. To this end, cold water can be supplied through the pipe coil 4.

The apparatus shown and described can be used without alteration for normal bleaching with a circulating, pulsating bleaching liquid.

However, a more rapid and considerably cheaper bleaching operation can be performed in the same equipment, if e. g. a hydrogen peroxide-water glass-aqueous caustic soda bleaching liquid is used, and the above pulsation step is replaced by a rapid and even heating of the bleaching-liquid-impregnated material to be bleached between the above-described two steps of removal of the major portion of the remaining liquid (in this case bleaching liquid) from the material by means of air and evacuation of the container 1. This heating step may be performed in the following manner:

For about 2 to 4 minutes a mixture of air and steam is blown through the material to be bleached at a pressure drop of about 0.1 kg. per sq. cm. For this purpose, steam is introduced through a valved conduit 27 and air through the valve 25. A mixture of air and steam having a temperature of 100° C. and a relative moisture content of about 100% may thus be easily obtained, whereby the material to be bleached will be heated without being dried. The temperatures before and after the container 1 will be checked by means of thermometers 28 and 29. After heating the bleaching material the valves 7, 24 and 27 will be closed, and the material will be allowed to remain in the container 1 e. g. for 40 to 60 minutes. The container 1 is externally heat-insulated, so that the temperature in the material to be bleached remains practically unaltered and equal to the predetermined temperature (about 100° C.). After finished bleaching the material may be rinsed as described above.

Having now particularly described the nature of my invention and the manner of the operation what I claim is:

1. An apparatus for dyeing, bleaching and other liquid treatment of a material in granular, threaded or fibrous form, comprising a closed container to receive the material to be treated, a closed vessel in which the treating liquid is prepared and stored, a pump having an intake and a discharge, a four port valve, a first conduit connecting the upper interior portion of said closed container to one of the ports of said valve, a second conduit connecting the upper interior portion of said closed vessel to a second port of said valve, third and fourth conduits connecting the third and fourth ports of said valve to the pump intake and the pump discharge, respectively, means for operating said valve to connect the intake and dis-

charge of said pump selectively to said first and second conduits to subject said container to higher and lower pressures than said vessel, other conduits connecting bottom interior portions of said container and said vessel for flow of treating liquid therebetween, and valves interposed in said other conduits adjustable to open and closed positions to allow and to prevent, respectively, flow of liquid between said container and said valve, a vent valve communicating with said fourth conduit adjustable between open and closed positions, said vent valve enabling said pump to withdraw air from said container and vent it to at least partially evacuate said container.

2. An apparatus as set forth in claim 1 comprising a source of compressed gas connected to one of said conduits to introduce gas under pressure into said container and maintain the treatment liquid at a constant superatmospheric pressure.

3. An apparatus as set forth in claim 2 comprising a source of steam connected to one of said conduits for supplying steam to the liquid impregnated material.

4. The apparatus set forth in claim 1 comprising means supporting said material in a position interposed between said other conduits for selective flow of treatment liquid therethrough in opposite directions and means for actuating said four port valve to alternately connect said container and vessel with said pump intake and discharge to set up pulsations in the treatment liquid.

5. An apparatus for treating granular, threaded and fibrous materials with liquid dye, bleaches and the like comprising a closed container having a hollow support for a material to be treated, a first conduit for delivering liquid to the interior of said support, said support having means insertable into the material through which liquid is delivered from said support to the interior of said material, a second conduit connected to the bottom of said container for supplying said liquid to the bottom of said container to immerse the material therein, a third conduit communicating with the upper portion of said container, a float valve in said third conduit for preventing discharge of said liquid through said third conduit, a receptacle for treating liquid connected to said first and second conduits, control valves in said first and second conduits adjustable to open and closed positions, a pump having an intake port and a discharge port, a selector valve having four ports, a fourth conduit connecting one of said selector valve ports to the upper portion of said receptacle, two of said selector valve ports being connected to the intake and discharge ports of said pump, respectively, and the fourth selector valve port being connected to said third conduit, said selector valve being adjustable to connect the intake and discharge ports of said pump selectively to said third and fourth conduits to produce selectively (1) a subatmospheric pressure in said container, (2) different superatmospheric pressures in said receptacle and container and (3) a subatmospheric pressure in said container and a superatmospheric pressure in said receptacle, and means for actuating said selector valve to connect the discharge port of said pump alternately to said receptacle and said container to alternately subject said receptacle to greater and lesser pressures thereby setting up pulsations in said liquid.

6. An apparatus for treating solid materials with liquids comprising a closed container for receiving the solid material, a closed receptacle for treating liquid, conduits connecting the receptacle to said container, means communicating with one of said conduits and insertable into the material and the other of said conduits communicating with the interior of said receptacle outside of said material, said conduits acting to supply liquid on opposite sides of said material in said receptacle, an air pump having an intake and a discharge, and means including conduits and a selector valve means connecting the intake and the discharge of said pump to said container and said receptacle above the level of liquid and material therein, said selector valve means being adjustable to connect

the intake and discharge of said air pump selectively to said container and receptacle to produce selectively (1) a subatmospheric pressure in said container and (2) different pressures in said receptacle and container.
